UNITED STATES PATENT OFFICE.

JOHN DESMOND, OF JACKSON, MICHIGAN, ASSIGNOR TO JAMES CAREY AND CHARLES RUTSON, BOTH OF SAME PLACE.

STEAM-EMPTYING ASH-PAN.

SPECIFICATION forming part of Letters Patent No. 297,507, dated April 22, 1884.

Application filed February 16, 1884. (No model.)

To all whom it may concern:

Be it known that I, JOHN DESMOND, a citizen of the United States of America, residing at Jackson, in the county of Jackson and State 5 of Michigan, have invented certain new and useful Improvements in Steam-Emptying Ash-Pans, of which the following is a specification, reference being had therein to the accompanying drawings.

10 My invention relates to a steam-emptying ash-pan for locomotives, by means of which the ashes therein collected, or snow and ice which also collects therein, may be at any moment ejected therefrom by the force of escaping steam; and it consists in the pan A, having the walls A', hinged outlet-gates a, and plates B, slotted ejector-pipes C, and steam-supply pipe D; in the method of supplying steam from the boiler, and in the construction, combination, and arrangement of the parts, substantially as hereinafter more fully shown and described.

15

In the drawings, Figure 1 is a plan view of my invention. Fig. 2 is a sectional side elevation thereof, and Fig. 3 is a detail view.

20 In the accompanying drawings, A represents a rectangular ash-pan having walls A', and the hinged outlet-gates a and a. The outlet-gates a have formed thereon the eyes b by turning over the upper edge thereof, through which are projected the hinge-bars b', which are rigidly secured in the longitudinal walls of the pan. Between the longitudinal walls are rigidly secured, by ordinary mechanical 25 expedient, the plates B. These plates are each

inclined at a slight angle upwardly from the bottom of the pan, and each plate has resting thereon a transverse ejector-pipe, which is slotted, as shown at C', Fig. 3, the slots thereof all facing one way and aligned with the plates 40 B, in order to eject the ashes. The slotted ejector-pipes C, slotted longitudinally at C', as shown, project through suitable orifices provided in the longitudinal walls of the ash-pan, and they are closed at their remote ends by 45 the caps f, and connect with the steam-supply pipe D by means of the pipe-joints f'. The steam supply pipe D leads to the boiler of the locomotive, from whence the steam is supplied, and near the point of such connection there is 50 provided an ordinary valve, which is operated by a lever.

Having described my invention, what I claim is—

1. In a locomotive ash-pan, the plates B, arranged with relation to the ejector-pipes C, having slots C' for ejecting the ashes from the bottom of the pan, substantially as shown, and for the purpose described. 55

2. In a locomotive ash-pan, the combination 60 of the pan A, having outlet-gates a a, plates B, ejector-pipes C, and steam-supply pipe D, substantially as shown, and for the purpose described.

In testimony whereof I affix my signature in 65 presence of two witnesses.

JOHN DESMOND.
